UNITED STATES PATENT OFFICE.

CYRUS A. ARNSBERGER, OF RUDY, IDAHO, ASSIGNOR OF ONE-TENTH TO
ROBERT A. CRAIG, OF RUDY, IDAHO.

WATER-MOTOR.

SPECIFICATION forming part of Letters Patent No. 731,835, dated June 23, 1903.

Application filed February 24, 1902. Serial No. 95,406. (No model.)

To all whom it may concern:

Be it known that I, CYRUS A. ARNSBERGER, a citizen of the United States, residing at Rudy, in the county of Fremont and State of Idaho, have invented a new and useful Water-Motor, of which the following is a specification.

The invention relates to a water-motor.

The object of the present invention is to improve the construction of water-motors and to provide an apparatus of this character which will be comparatively simple and inexpensive in construction and which will be adapted to obtain its power from a body of water, such as a stream or the like.

15 The invention consists in the construction and novel combination and arrangement of parts hereinafter fully described, illustrated in the accompanying drawings, and pointed out in the claims hereto appended.

20 In the drawings, Figure 1 represents an elevation of a water-motor constructed in accordance with this invention. Fig. 2 represents a plan view thereof. Fig. 3 represents a vertical sectional view of the power-wheel. Fig. 4 represents a vertical section taken on line 4 4 of Fig. 2.

Like numerals of reference designate corresponding parts in all the figures of the drawings.

30 1 designates a rotary power-wheel having a hollow hub 5, fixed at one end to a stub-shaft 2, journaled in suitable bearings of a supporting-frame 3, and rotatably mounted at its other end on a pipe 4, which forms a conduit for conducting water from an elevated source of supply to the interior of the power-wheel. This tube or pipe 4, which may be connected at its upper end with any suitable elevated source of supply and which extends 35 at least to the top of the power-wheel, so that the water flowing through the pipe will rise to the top of the arms of the wheel, is bent at its lower end to form a trunnion for one end of the wheel-hub 5, a stuffing-box 2' of the usual construction being provided. The hub 5 of the wheel is flanged, as at 6, between which are disposed a plurality of arms 8. These arms are provided at their inner ends with sleeves, as 5', which are pivoted at 9 at one side 40 thereof to the flanges of the hub, and the

arms are connected by short stems 9^a with valves 10, arranged within the hollow hub 5 and adapted to close on suitable seats 11, whereby the flow of water through said arms will be cut off, as hereinafter explained. The 55 arms 8, which are shown arranged in two series, one series at each end of the hub 5, may be of any desired number and of any desired capacity, and in the form illustrated six arms are shown, three radiating from 60 the periphery of the hub at one end thereof and three from the other end, the arms of one series being arranged to alternate with those of the other series. These arms are hollow, and those of each series on the descending side of the wheel are designed to be supplied with water, whereby they are weighted to cause a rotation of the wheel, while those on the ascending side of the wheel are empty. The pivots 9 are arranged at the rear 70 edges of the inner ends of the arms, and those arms on the descending side of the power-wheel, as shown in Fig. 3, will hold the valves 10 open, so that the water will rise in the uppermost arm, and as the outer ends 12 of the 75 arms are open the said arms will continue weighted until they descend sufficiently to permit the water to drain from them, and they will be completely emptied by the time they arrive at the bottom of the wheel. The upward movement of the arms, as shown at the left of Fig. 3, causes the arms to swing backward or outward by gravity, and this movement operates to draw the valves firmly against the valve-seats, whereby the flow of 80 water to the arms at the ascending side of the wheel is positively cut off. By this construction and arrangement the descending side of the power-wheel is always heavier than the ascending side, and it will be clear that as 85 long as the supply of water continues the power-wheel will be rotated. The hollow arms, which are open at their outer ends, may be constructed in any suitable manner to form water-receiving chambers or buckets, 90 and these chambers or buckets may be made of any desired size to provide a motor of the desired power.

Changes in the form, proportion, size, and the minor details of construction within the 100

scope of the appended claims may be resorted to without departing from the spirit or sacrificing any of the advantages of this invention.

What I claim is—

- 5 1. In an apparatus of the class described the combination of a power-wheel having a hollow hub portion and provided with a series of arms movably connected with the hub portion and capable of independent movement, valves operated by the independent movement of the arms for controlling the flow of water to the same, and means for supplying the wheel with water, substantially as described.
- 15 2. In an apparatus of the class described, the combination, of a power-wheel having a hollow hub and provided with hollow arms pivotally mounted on the hub and open at their outer portions, valves connected with 20 the arms for controlling the flow of water to the same and arranged to shut off the flow of

water to the arms at one side of the wheel, and means for supplying the wheel with water, substantially as described.

3. In an apparatus of the class described, 25 the combination, of a power-wheel having a hollow hub provided with interior valve-seats, hollow arms movably mounted on the hub, valves arranged within the hub and connected with the arms and automatically operated 30 by the same, whereby the valves at one side of the wheel are closed, and means for supplying the wheel with water, substantially as described.

In testimony that I claim the foregoing as 35 my own I have hereto affixed my signature in the presence of two witnesses.

CYRUS A. ARNSBERGER.
